UNITED STATES PATENT OFFICE.

ALBERT J. KAELIN, OF HOUSTON, TEXAS.

FLEXIBLE SCRAPER.

SPECIFICATION forming part of Letters Patent No. 353,863, dated December 7, 1886.

Application filed June 8, 1886. Serial No. 204,467. (No model.)

To all whom it may concern:

Be it known that I, ALBERT J. KAELIN, of Houston, in the county of Harris and State of Texas, have invented a new and Improved 5 Flexible Scraper, of which the following is a specification, reference being had to the annexed drawings, forming a part thereof, in which—

Figure 1 is a side elevation of a scraper embodying my improvement. Fig. 2 is a section taken on line xx in Fig. 1. Fig. 3 is a transverse section taken on line yy in Fig. 1.

Similar letters of reference indicate corresponding parts in the different figures of the drawings.

My invention relates to improvements in flexible scrapers; and it consists in the peculiar construction and arrangement of parts, as hereinafter fully described, and pointed out 20 in the claim.

To the end of the handle A is secured a concave board, B, having opposite edges curved or outwardly convex, and to the back of the convex surface of the board B are secured metallic sockets a , for receiving the braces b , which are held in metallic sockets c , secured to the handle A. By means of this construction the strength of the connections between the braces and the handle and concave board 25 is insured by the metal, while lightness is secured by the employment of wood for the handle, concave board, and braces.

To the concave face of the board B is attached an oblong sheet of rubber, C, by means of bolts d , passing through washers e , through the rubber sheet C, board B, and into nuts f at the back of the board. The edges of the rubber sheet C project beyond the edges of the concave board B, so that when the scraper is in use only the rubber will be presented to the 35 floor or other surface being cleaned. By applying the scraper to the floor at the proper angle the entire edge of the rubber sheet C will be brought into contact with the floor, and as the scraper is moved forward its concave form will cause it to retain most of the 40 water which it gathers up, and to carry it forward.

Having thus described my invention, what I claim as new, and desire to secure by Letters 45 Patent, is—

The herein-described flexible scraper, consisting of the concave board A, the sheet of rubber, C, secured by bolts d to the concave face of the board, the handle A, the sockets 55 a c , secured to the convex face of the board and handle, respectively, and the braces b , as specified.

ALBERT J. KAELIN.
